TYPEWRITING MACHINE

Edwin S. Hall, New Haven, Conn.

Application August 6, 1937, Serial No. 157,741

23 Claims. (CL 197—27)

This invention relates to typewriting machines. Modern typewriter manufacture has attained a high degree of excellence and much progress has been made in reducing the noise of operation. In the so-called "noiseless" machines, the noise of impact of the type with the platen is reduced usually by checking the velocity of the type with a straightening toggle before the type reaches the platen, and then pressing it home either by a direct linkage with the key lever or by using the kinetic energy given up by the stopping of a rapidly moving weight. Type bar actions of this nature have been highly perfected and do excellent work, but their "touch" is not liked by some operators and they seem to be of such nature as to preclude the use of a case shift of the segment type, requiring that the carriage be raised or lowered for case shift purposes. Case shift mechanisms which raise or lower the carriage are heavier in operation, more tiring to hands and eyes of the operator, and tend to be more noisy than those which raise or lower the segment in which the type bars are pivoted. In fact, modern typewriters of the ordinary front-strike variety, by the use of a quiet segment shift and by quieting the escapement and other sources of mechanical noise, are now more quiet than the "noiseless" machines in every respect save that of the noise of impact of the type on the platen. An object of this invention is to provide a different and better method of quiet printing in a typewriter, using the end thrust of a toggle directly to obtain the printing pressure with a rolling contact of the type with the platen, and permitting simpler and quieter shift means, independent of both carriage and segment, for selecting which type character of a given type bar is to be printed. A further object is to provide a type bar action of such nature as to permit the use of two or three times the usual number of type characters on each type bar, either to permit the number of type bars to be correspondingly reduced, or to make it possible for an office or portable typewriter to have two type faces instead of one, or many more characters as desired, all under immediate and convenient control of the operator.

More specifically, objects of this invention are:

To provide an improved and relatively silent or noiseless method of printing in a typewriter by using a rolling contact of the type on the platen, the approach of the type to the platen being substantially tangential rather than normal;

To provide an improved method of printing in

a typewriter by the direct application of the potential pressure or end thrust of a toggle type bar as it is driven over-center, to produce clean-cut printing and an ample number of carbon copies quietly and rapidly with a rolling contact of the type with the platen;

To provide an improved method of printing in a typewriter such that the uniformity of strength of the type impressions will depend more upon the machine itself and less upon the uniformity of touch of the operator;

To provide an improved method of printing in a typewriter by rolling the type impression onto the platen on both the forward and the return strokes of the type-bar;

To provide an improved method of printing with a rolling contact by rolling the type impression onto the platen on one stroke only of the type bar, the type being withdrawn from the platen on the other stroke;

To provide an improved method of shifting from lower to upper case in a typewriter by use of a control member independent of and without raising or lowering either the platen or the segment in which the type bars are pivoted;

To provide improved type bar and case shift actions for carrying out these improved methods;

To provide type bar actions in which each type bar consists of two members, the bar itself and a separate type carrier pivoted thereto;

To provide type bar actions in which the motion of approach of the type is essentially tangential instead of normal to the platen, and in which the printing pressure is obtained by a rolling or toggle action as the type carrier rolls past the printing point;

To provide type bar actions in which the type carrier has a cycloidal movement, the type itself following a portion of a hypocycloid while approaching the platen, so that, while printing, the instantaneous axis of rotation of the type carrier is the printing point;

To provide type bar actions in which, when shifting from lower to upper case with the usual shift key, neither the platen nor the segment in which the type bars are pivoted need be raised or lowered, the shift being made by moving a control element independent of both carriage and segment;

To provide type bar actions in which it is conveniently possible to have more than the usual two or three characters on each type bar, together with convenient and easily operable means for selecting which of the several characters is to

be printed upon operation of the corresponding key;

To provide type bar actions in which, with two or three pairs of characters on each type bar, it is possible to predetermine which pair is to be used, and then shift from one character to the other of that pair by the usual movement of the shift key;

To provide a type bar action which, by the use of an over-center toggle type bar, is capable of rolling the type impression onto the platen on the forward stroke of the type bar without touching the type to the paper on the return stroke;

To provide fast, effective, and efficient type bar and case shift actions, relatively simple and direct, consisting of few parts, and capable of being built within the limits of relatively small machines.

Briefly described, the invention consists essentially of pivoting the type bars in a segment coplanar with the axis of the platen so that the type bars swing substantially tangent to the platen instead of normal to it. Each type bar comprises two members, pivoted together, arranged to form a toggle, to roll the type impression onto the platen as the toggle goes over-center. Various means may be provided to control the rolling action of the type, including internal gearing, planetary gearing, and cycloidal cams, the timing of the gears or the positioning of the cams being used to control the case shift or other selection of which type character of a given type bar is to be printed upon operation. This improved shift control or selection mechanism, being independent of both carriage and segment, can be light and quiet in operation and can have a wider range, permitting the convenient use of four or more characters on each type bar instead of the usual two.

In the drawings, Fig. 1 is a sectional elevation of an embodiment of the invention, illustrating the principle thereof; Fig. 2 is a plan view of some of the parts of Fig. 1; Fig. 3 is a sectional elevation of another embodiment of the invention; Fig. 4 is a plan view of some of the parts of Fig. 3; Fig. 5 is a sectional elevation of another embodiment of the invention, similar essentially to the embodiment of Fig. 3; Fig. 6 is a plan view of some of the parts of Fig. 5; Fig. 7 is a sectional elevation of another embodiment of the invention; Fig. 8 is a front view of the type guide assembly of Fig. 7; and Fig. 9 is a plan view of some of the parts of Fig. 7.

Referring to the drawings, a different embodiment of the invention is shown on each of the four sheets. In each case, the carriage, paper, ribbon, ribbon vibrator, and various other parts have been omitted for clearness in the drawings, but it is understood that the platen should be mounted on a carriage in a well-known manner, and that the paper, ribbon, etc. should be provided as usual.

Referring to Figs. 1 and 2, platen 10 and arcuate segment pivot rod 13 are mounted in coplanar relationship in frame 11, the axes of platen 10 and segment pivot rod 13 being in a common horizontal plane. A number of type bars 12, (preferably the usual number), are pivoted on segment pivot rod 13, and are actuated by links 14 connecting with key levers 15, return springs (not shown) being provided as usual. Type guide 17 is fixed on frame 11 adjacent the printing point on platen 10, to position the type when printing and to form a reaction surface for the side thrust of the type bars toward the ends of the segment

whose thrust cannot be normal to platen 10. Type guide 17 may also serve as a support or track for the ribbon vibrator (not shown) in the usual manner.

Each type bar 12 carries a type wheel 16 pivoted thereon. Each type wheel 16 may have six or more type characters on the ends of its radiating arms 28. Each type wheel 16 has a pinion 18 fixed thereto and in mesh with idler 19, also pivoted on type bar 12, and in mesh with sun gear 20. Sun gear 20 is pivoted adjacent to type bar 12 on segment pivot rod 13, and all the sun gears 20 (one for each type bar 12) are in mesh with arcuate rack 21. Rack 21 is urged upward by springs 22 and is positioned by link 23 having hooks 24 engaging pin 25 on rack 21. Link 23 is connected to shift key lever 26.

In operation, because of the coplanar relationship of platen 10 and arcuate segment pivot rod 13, type bars 12 swing in an arc substantially tangent to platen 10 instead of in the usual normal manner.

If any type wheel 16 could roll without slipping and in proper timed relationship on the inside of a spherical surface whose section would be indicated by the broken line 27, one of the type characters of type wheel 16 would roll its impression onto the paper on platen 10 while type bar 12 passes the position where its axis intersects the axis of platen 10. By changing the timed relationship, another of the type characters could be selected to be printed upon operation of key lever 15. A segment of a spherical internal gear, or of an annular crown gear, might be used with the radial arms of type wheel 16 as gear teeth meshing directly therewith, but the pitch surface of such a gear should be tangent to the printing point on platen 10, wherefore its teeth would have to be cut away in the region where they are most needed. Moreover such a gear would not be adaptable to changing the timing to select which of the type characters of type wheel 16 is to be printed.

Type wheels 16 can, however, be made to roll as though in mesh with such a gear, by planetary gearing as shown, the proportions of the various parts being correctly chosen. When key lever 15 is depressed, type bar 12 swings upward, idler gear 19 rolls around stationary gear 20 and drives pinion 18, which causes type wheel 16 to roll without slipping on arc 27, until one of the type characters is impressed upon the paper on platen 10 by toggle action of type bar 12 and wheel 16 as wheel 16 rolls by. Type bar 12 need be raised only enough to print the upper edge of the type character, and then it may be permitted to return toward the rest position, reinforcing the type impression as it starts on the return stroke.

If shift key lever 26 had been depressed before key lever 15 had swung into printing position, the timing of type wheel 16 would have been changed by the corresponding movement of rack 21, sun gear 20, idler 19, and pinion 18, so that the next type character below that printed would have been selected for printing instead. To select either of the other two pairs of type characters on type wheel 16, link 23 may be changed to another hook 24 on pin 25, moving rack 21 to a different position, adjusting sun gears 20 and setting type wheels 16 in a different timed relationship. Thus three different type faces or sets of type characters could be used on one machine, the shift from one type face to another being managed by change of the setting of link 23 relative to rack 21, and the shift from lower to

upper case in any of the three type faces being made by the shift key in the usual manner.

Referring to Figs. 3 and 4, platen 30 and arcuate segment pivot rod 33 are mounted in coplanar relationship in frame 31, their axes being in a common plane. Type bars 32 are pivoted on rod 33 and are actuated by links 34 connecting with key levers 35. Type guide 37 is fixed adjacent the printing point on platen 30 to guide the type when printing to resist side thrust of the "cranked" type bars, and to support the ribbon vibrator in the usual manner.

To each type bar 32 is pivoted a type carrier 36 having preferably four or more different type characters on the ends of radiating arms 38. On another radiating arm of type carrier 36, roller 39 is operably mounted. Expanding spring 40 normally holds carrier 36 in such a position relative to type bar 32 that, upon operation of type bar 32, its roller 39 will engage cam 41 which is mounted in frame 31 in such a manner that it can be rotatably positioned in several positions about the center of pivot rod 33 as a center. Arcuate tail rod 42 of cam 41 is engaged by bell-crank 43 which is freely pivoted on jackshaft 44. Arm 45 is fixed on jackshaft 44 and is connected by link 46 to shift key lever 47. Notched arm 48 is also fixed on jackshaft 44 and its notches may be engaged by latch 49 of bellcrank 43 to lock bellcrank 43 to jackshaft 44 in either desired position.

In operation, because of the coplanar relationship of platen 30 and arcuate segment pivot rod 33, type bars 32 swing in arcs substantially tangent to platen 30 instead of in the usual normal manner. When any key lever 35 is depressed, its corresponding type bar 32 swings downward and its roller 39 engages cam 41, the engagement being quiet because cam 41 is substantially tangent to the path of roller 39 at engagement. The contour of cam 41 then curves easily into a hypocycloid such that, by its action on roller 39, each of the type characters on arms 38 is caused to follow another hypocycloidal path, the type character pre-selected for printing following that path which reaches platen 30 at the printing point when the pivot center of type carrier 36 on type bar 32 passes thru the plane common to the axes of platen 30 and segment pivot rod 33. At this instant, the instantaneous center about which type carrier 36 is rotating, is the printing point. This rolling action is geometrically the same as that obtained by the gearing shown in Figs. 1 and 2. In either case, the velocity of approach of the type to the platen at the instant of contact is almost zero and the contact therefore quiet, the printing pressure being obtained by the direct application of the end thrust of the toggle formed by the type bar and the type wheel or carrier as the toggle goes over-center, the platen being set close enough to make the desired pressure.

To select a different type character on another of radiating arms 38, it is only necessary to change the position of cam 41. Four positions are indicated by the dash lines in Fig. 3, one for each of the four type arms 38 of each type bar 32. Depressing shift key lever 47, (acting thru link 46, arm 45, jackshaft 44, arm 48, latch 49, and bellcrank 43), moves cam 41 into the next position above that now occupied, and causes the next type character below that shown in printing position to print. Engagement of latch 49 in the other notch of arm 48 will move cam 41 to the third position, and thereafter depression of shift key lever 47 will move cam 41 into the highest po-

sition indicated. In this way the operator may conveniently select which of the four type characters is to be printed upon operation of the type bar. The same sort of mechanism could be extended to six or more type characters on each type bar. In principle it is the same as that shown in Figs. 1 and 2. In either case, the case shift and the selection of type face, etc. may be obtained without raising or lowering either the carriage or the segment, the control means being independent of both carriage and segment.

The embodiment shown in Figs. 5 and 6 is a further development of the idea illustrated in Figs. 3 and 4, the arrangement and proportions of the type bar action being somewhat different. Platen 50 and arcuate segment pivot rod 53 are mounted in coplanar relationship in frame 51 with their axes in a common inclined plane. Type bars 52 are pivoted on rod 53 and are actuated by links 54 connecting with key levers 55. Type guide 57 is fixed adjacent the printing point on platen 50 to guide the type when printing, to resist the side thrust of the "cranked" type bars, and to support the ribbon vibrator (not shown) in the usual manner.

To each type bar 52 is pivoted a type carrier 56 having preferably four or more different type characters on the ends of radiating arms 58. On another radiating arm of type carrier 56, roller 59 is operably mounted. Spring 60 holds roller 59 in the groove of its cam member 61. A cam member 61 is provided for each type bar 52, and both cam member 61 and type bar 52 are pivoted on segment pivot rod 53, cam member 61 being cleft to straddle type bar 52 in the region of the 35

50 pivot. Each of the cam members 61 has a roller 62 bearing against an arcuate ramp member 63 so arranged that by its vertical movement, all cam members 61 can be simultaneously positioned rotatably about segment pivot rod 53. Operating connections between ramp member 63 and the shift key lever are not shown; obviously constructions similar to those shown in Figs. 1 and 2 connecting rack 21 with shift key lever 26 could be applied whereby the operator could conveniently move ramp member 63 to position cam members 61 in any one of the four positions indicated by broken lines in Fig. 5, to select the corresponding type character on arms 58 for printing.

In operation, because of the coplanar relationship of platen 50 and arcuate segment pivot rod 53, type bars 52 swing in arcs substantially tangent to platen 50. When any key lever 55 is depressed, its corresponding type bar 52 swings upward, roller 59 following cam 61 to control the motion of type carrier 56 so that one of the type characters on arms 58 is brought into rolling contact with platen 50 at the printing point as the 60 toggle consisting of type bar 52 and type carrier 56 goes over-center. To predetermine which of the four type characters on type carrier 56 is to be printed, it is only necessary to position cam 61 in the right one of its four positions. Movement 65 of arcuate ramp member 63 downward from the position shown will shift all cams 61 simultaneously to any desired position.

The fact that the embodiment shown in Figs. 3 and 4 has a down-strike action while this one shown in Figs. 5 and 6 has an up-strike, does not alter the fact that the two embodiments are essentially similar. In both, rolling action of the type while printing is obtained by movement of a roller mounted on an arm of the type carrier in 75

rolling engagement with a cam having a cycloidal contour so that the type also must have a cycloidal movement, and the selection of which type character is to be printed is determined by the positioning of the cam. In the latter embodiment, the proportions of type bar 52 and type carrier 56 are those of a rolling circle one-half the diameter of the circle within which it rolls, and the hypocycloids generated are diameters of the larger circle. The active part of cam 61, therefore, is a straight line, and when roller 59 follows such a straight path, each of the type characters on the ends of arms 58 follows a similar straight hypocycloidal path as though on the periphery of a circle rolling on the inside of a circle twice the size. Again, at the rolling contact of the type character with platen 50, the velocity of approach of the type character to the platen is almost zero and the contact therefore quiet, the printing pressure being obtained by the end thrust of the toggle consisting of type bar 52 and type carrier 56 as the toggle goes over-center. The type impression is reinforced by the reversed rolling action as type bar 52 starts returning.

25 Return of the type bar to the position of rest, upon release of key lever 55, is caused by gravity aided by the usual return spring (not shown).

Referring to Figs. 7, 8, and 9, platen 70 and arcuate segment pivot rod 73 are mounted in a coplanar relationship in frame 71, their axes being in a common plane. Type bars 72 are pivoted on rod 73 and are actuated by links 74 connecting with key levers 75. Return springs 87 are provided to return type bars 72 to the position of rest. Type guide 77 is fixed adjacent the printing point on platen 70 to guide the type when printing, to resist side thrust of the "cranked" type bars, to support the ribbon vibrator (not shown) in the usual manner, and to provide a type guide aperture 79. Nearby the cushion 83 is supported by shift rod 84 which latter is slideable through holes in type guide 77 and operably connected to shift key lever 85 by lever 86 and shaft 89.

40 To each type bar 72 is pivoted a type carrier 76 having two or more different type characters on the ends of radiating arms 78 which arms 78 are shaped like gear teeth to engage the upper and lower sides of aperture 79 as internal gear teeth in rolling relationship. The pivotal movement of type carrier 76 on type bar 72 is limited to the region centering on that in which the two members are in line by pin 81 carried by carrier 76 and operable between limits set by ears 82 on the end of type bar 72. C-spring 80 by its compressive action tends to cause type bar 72 and type carrier 76 to buckle one way or the other to the limit of their pivotal action as permitted by pin 81 and ears 82. When in the position of rest, type carriers 76 are supported by cushion 83.

In operation, the position of cushion 83 is determined by that of shift key lever 85. As shown, shift key lever 85 is depressed as for printing upper case letters and cushion 83 is in its upper position. Upon operation of key lever 75, type bar 72 swings upward from its position of rest to the position shown by dotted lines whereupon type carrier 76 engages cushion 83. Continued upward movement of type bar 72 causes the toggle to straighten, driving the lower radiating arm 78 of type carrier 76 into aperture 79, causing its type character to roll the impression of the type onto the platen as the toggle goes over-center as shown by the short dash lines. Shortly thereafter, the printing having been done, C-spring 80

snaps the toggle to its bent position as shown by long dash lines, withdrawing the type from the platen. When the key is released, return spring 87 helps type bar 72 to swing back downward with sufficient force to drive the toggle over center again when type carrier 76 strikes cushion 83, returning the parts to the position of rest shown in full lines in Fig. 7.

If shift key lever 85 had been in its released position, indicated by dotted lines, cushion 83 would have had a lower position, and upon operation of key lever 75, type carrier 76 would have engaged cushion 83 earlier so that its upper radiating arm 78 would have entered aperture 79, printing the lower case letter. While but two radiating arms 78 for two type characters are shown on each type carrier 76, it is obvious that three or more could be used, and a corresponding number of positions provided for cushion 83 by selector mechanisms associated with shift key lever 85 similar in construction and arrangement to those illustrated in Figs. 1 to 4 inclusive.

Having thus described the invention, it will be obvious that all the objects thereof as above stated have been attained. In each of the four embodiments shown in Figs. 1 to 9 inclusive, the movement of the type bar is essentially tangential to the platen instead of normal to it; the printing is not done by a direct impact but by a rolling contact of the type on the platen (thru ribbon and paper), such a rolling contact being inherently much more quiet than any impact could be; the printing pressure is obtained by the direct application of the end thrust of a toggle as it goes over-center—a simpler and more positive action than to use a toggle to check the velocity of the type and then press it home by other means; the amount of printing pressure is dependent upon the setting of the platen relative to the toggle of the type bar, rather than upon the touch of the operator; more than the usual two characters can be used on each type bar, and the control means for selecting which type character is to be printed is independent of both carriage and segment, lighter and quieter in operation.

While I have shown specific embodiments of the invention, it will be understood that changes may be made in the arrangement and in the construction of the various parts without departing from the scope of the following claims.

I claim:

1. In a typewriter having a platen, a normally stationary type bar comprising two members pivoted together, type on one of said members, and means for swinging said type bar in a manner substantially tangent to said platen and for causing said type to have a rolling contact with said platen.

2. In a typewriter having a platen and a fixed frame, a type bar pivoted to and normally stationary relative to said frame, a type carrier pivoted to said type bar and forming a toggle with said type bar, type on said type carrier, and means for moving said type carrier in such a manner as to cause said type to be impressed on said platen with a rolling contact as said toggle goes over-center.

3. In a typewriter having a platen and a fixed frame, a type bar pivoted to and normally stationary relative to said frame, a type carrier pivoted to said type bar, type on said type carrier, and means for moving said type along a cycloidal path as it approaches said platen so that, while printing, the instantaneous axis of rotation of 75

said type may be the printing point on said platen.

4. In a typewriting machine, a fixed frame, a platen operably mounted on said frame, a plurality of type bar members normally stationary relative to said frame, pivots for said type bar members in said frame, the axes of said pivots and of said platen being in a common plane, type characters carried by said type bar members, means for swinging said type bar members toward said platen, and means for causing said type characters to print on said platen with a rolling contact.

5. In a typewriting machine, a frame, a platen operably mounted on said frame, type bar members, pivots for said type bar members in said frame, a plurality of pairs of type characters on each of said type bar members, means for predetermining which of said pairs of type characters is to be available for printing, and means including a shift key lever for predetermining which type character of a given pair is to be printed upon operation of a type bar member, both said predetermining means being independent of and requiring no relative movement between said platen and said pivots.

6. In a typewriting machine, a frame, a platen operably mounted on said frame, type bar members, pivots for said type bar members in said frame, a plurality of pairs of type characters radially positioned on the ends of each of said type bar members, means for predetermining which of said pairs of type characters is to be available for printing, and means including a shift key lever for predetermining which type character of a given pair is to be printed upon operation of a type bar member, both said predetermining means being independent of and requiring no relative movement between said platen and said pivots.

7. In a typewriting machine, a frame, a platen operably mounted on said frame, type bar members, pivots for said type bar members in said frame, type carriers pivoted upon said type bar members, a plurality of pairs of type characters on said carriers, means for predetermining which of said pairs of type characters is to be available for printing, and means including a shift key lever for predetermining which type character of a given pair is to be printed upon operation of a type bar member, both said predetermining means being independent of and requiring no relative movement between said platen and said pivots.

8. In a typewriting machine, a platen, a plurality of type bars, a type wheel pivoted on each of said type bars, a plurality of type characters on each of said type wheels, and gearing for controlling the rotation of any type wheel during movement of its type bar into printing position relative to said platen, so as to cause one of said type characters to roll its impression onto said platen.

9. The invention as described in claim 8, with means for timing said gearing to select which one of said type characters is to be printed.

10. In a typewriting machine, a platen, a plurality of type bars, a type carrier pivoted on each of said type bars, a plurality of type characters radially arranged on each of said carriers, a cycloidal cam member, and means on each of said carriers for operably engaging said cam member upon movement of said carrier toward said platen to cause said type characters to follow cycloidal paths on approaching said platen.

11. The invention according to claim 10, with

means for positioning said cam member to select which of said type characters on any of said type carriers is to be printed upon operation.

12. In a typewriting machine, a frame, a platen operably mounted on said frame, a type guide member fixed to said frame adjacent said platen, a plurality of type bars operably pivoted in said frame, a type carrier pivoted to each of said type bars, a plurality of type characters radially arranged on each of said carriers, a cam member, and means on said carriers for operably engaging said cam member upon movement of said carrier toward said platen, said cam member and said means being so constructed and arranged as to cause one of said type characters to have a rolling contact with said platen as said type character passes said type guide member.

13. The invention as claimed in claim 12, with means including a shift key lever for positioning said cam member to select which of said type characters on any of said type carriers is to be printed upon operation.

14. In a typewriting machine, a fixed frame, a platen operably mounted on said frame, a plurality of type bar members pivoted to and normally stationary relative to said frame, each of said members comprising a type bar and a type carrier pivoted to said type bar and forming therewith a toggle and type characters radially positioned on the end of said carrier, and means for causing one of said type characters to print on said platen with a rolling contact as said toggle goes over-center.

15. In a typewriting machine, a platen, a plurality of type bar members each comprising a type bar and a type carrier pivoted to said type bar and forming therewith a toggle and type characters radially positioned on the end of said carrier, means for causing one of said type characters to print on said platen with a rolling contact as said toggle goes over-center on one stroke of said type bar member while preventing any printing during the return stroke thereof, said means comprising spring means urging said toggle in either direction away from its straightened position.

16. In a typewriting machine, a platen, a plurality of type bar members, a plurality of type characters on each of said type bar members, a type guide member adjacent said platen, an aperture in said type guide member substantially defining the printing point on said platen, and means for causing any desired one of said type characters to enter said aperture to print upon said platen with a rolling contact upon operation of the corresponding type bar member.

17. In a typewriting machine, a platen, a plurality of type bar members, a plurality of type characters on each of said type bar members, a type guide member adjacent said platen, said guide member having an aperture therein, means for causing one of said type characters to print upon said platen with a rolling contact through said aperture upon operation of its type bar member, and means for selecting which of said type characters shall enter said aperture for printing upon said operation.

18. In a typewriting machine, a frame, a platen operably mounted on said frame, a plurality of type bar members each comprising a type bar and a type carrier pivoted to said type bar and forming therewith a toggle and a plurality of type characters radially positioned on the end of said carrier, pivots for said type bar members on said frame, means for causing one of said type characters to print on said platen with a rolling contact as said toggle goes over-center on one stroke of said type bar member while preventing any printing during the return stroke thereof, said means comprising spring means urging said toggle in either direction away from its straightened position.

acters to print on said platen, and means for pre-determining which of said type characters on a given carrier is to be printed upon operation of the corresponding type bar member, said pre-determining means being independent of and requiring no relative movement between said platen and said pivots.

19. In a typewriting machine, a frame, a platen, a plurality of type bar members each comprising a toggle and each carrying a plurality of type characters at one end and pivoted to said frame at the other end, a type guide adjacent said platen, a stop associated with said type guide for limiting the motion of the type carrying end of any type bar member whereupon further motion of said member causes its toggle to go over-center while printing one of said characters, and shift means for controlling the position of said stop to predetermine which of said type characters will be printed.

20. In a typewriting machine, a frame, a platen, a plurality of type bar members each comprising a toggle and each carrying type at one end and pivoted in said frame at the other end, a type guide adjacent said platen, a stop associated with said type guide to limit the motion of the type carrying end of any type bar member whereupon further motion of said member causes its toggle to go over-center during the printing operation, and a stop to limit the return motion of said type carrying end whereupon further motion of said type bar member causes its toggle to reverse over-center to the position of rest.

21. In a typewriter having a platen and type for printing thereon, means for reducing the noise of contact of said type with said platen comprising means for mounting said type for swingable movement in opposite directions toward and

away from a printing position at said platen along arcs substantially tangent instead of normal to said platen, means for so moving said type, and means effecting rolling contact of said type with said platen upon arrival thereof at said printing position.

22. In a typewriter having a platen and type for printing thereon, means for reducing the noise of contact of said type with said platen comprising means for mounting said type for swingable movement in opposite directions toward and away from a printing position at said platen along arcs substantially tangent instead of normal to said platen, means for so moving said type, and means effecting rolling contact of said type with said platen upon arrival thereof at said printing position and again upon departure thereof from said printing position.

23. In a typewriter having a platen and a plurality of type carrying members each having a plurality of type characters, means for both pre-determining which of said type characters is to be printed upon operation of the corresponding carrying member and for reducing the noise of contact of said type character with said platen, said means comprising means pivotally mounting said carrying members for swingable movement of said type characters in opposite directions toward and away from a printing position at said platen along arcs substantially tangent instead of normal to said platen, means for so moving said members, and control means predetermining which of said characters is to be printed upon operation of its carrying member and effecting rolling contact of said type character with said platen as it arrives at said printing point.

EDWIN S. HALL.
